FASTENING MEANS FOR ABUTTING FLAPS
OF FLEXIBLE CARRIERS OR CARTONSClaude D. Keith, New York, N. Y., assignor of
one-half to Charles E. Culpeper, Norwalk,
Conn.

Application July 23, 1935, Serial No. 32,745

3 Claims. (Cl. 224—45)

This invention relates to improvements in fastening means for abutting flaps of flexible carriers or cartons preferably composed of cardboard, paper or like material.

5 One of the objects of this invention is to provide integral fastening means for the abutting flaps of flexible containers, cartons or carriers which will take advantage of the flexibility of the carton to permit relative sliding movement of the flaps for engagement and disengagement of the fastening members.

10 Another object of my invention is to provide fastening tongues formed integrally or unitarily with the flaps which will produce relatively inexpensive fastening means that will fasten and retain the flaps in securely fastened position.

15 Another object of my invention is to provide fastening tongues which in their fastening and unfastening movements may be readily and quickly manipulated and will not bind, stick or become jammed in such operations.

20 Another object of my invention is to provide fastening tongues from material which would be cut out to form hand holes or carrying handle for the carrier, carton, or the like.

25 Still another object of my invention is to provide a device of the type specified having fastening tongues which will each have only one fold and which in folded position may be utilized to space bottles carried by the carrier or carton.

30 In general terms, my invention comprises the provision in a flexible body having abutting flaps, of a pair of tongues cut out from the material of the flaps and so severed as to provide bendable tongues having base portions connected with their respective flaps and offset laterally with respect to each other, and kerfed portions between said flaps and tongues in alignment with said base connecting portions and also offset laterally with respect to each other, said tongues being initially bendable about said base connecting portions, which form axes coinciding with the bottom of the tongues, to enable interengagement upon relative sliding of the flaps, and thereafter being again bendable or foldable about said connecting portions to cause projection at right angles through the openings in the opposite flaps and, after such projection to abut at its outer edge against the bottles or goods carried by the carrier or carton.

35 More particularly, I provide said bendable tongues with ends tapered into tips of small radius and spaced from the adjacent edge of the handle opening to enable ready engaging and disengaging sliding movements and preferably

the leading ends of the tongues each have a gradual curve extending from the base to a tip above the longitudinal center line of the tongue and a sharp curve above said center line, while the opposite ends of said tongues are curved in the opposite direction.

40 With these and other objects in view, the invention comprises the combination of members and arrangement of parts so combined as to co-act and co-operate with each other in the performance of the functions and the accomplishment of the results herein contemplated, and comprises in one of its adaptations the species or preferred form illustrated in the accompanying drawing, in which:—

45 Fig. 1 is a view in side elevation showing a bottle-carrier or carton embodying my invention just before engagement of the fastening tongues;

50 Fig. 2 is a side elevation of the carton shown in Fig. 1 after engagement and folding of the tongues;

55 Fig. 3 is an end elevation of the fastened carton shown in Figs. 1 and 2;

60 Fig. 4 is a section on the line 4—4 of Fig. 2 looking in the direction of the arrows;

65 Fig. 5 is a section on the line 5—5 of Fig. 2, looking in the direction of the arrows;

70 Fig. 6 is a section on the line 6—6 of Fig. 2 looking in the direction of the arrows;

75 Fig. 7 is a view in plan of a strip of paper cut to produce the carton and fastening device shown in Figs. 1 to 6, and

80 Fig. 8 is a view in side elevation of a pair of flaps showing a slightly modified form or shape of tongues.

85 Referring now to the drawing which illustrates my fastening means applied to a bottle carrier or carton, which, except for the provision of a flexible body or strip, forms no part of my invention, I indicates a body or strip of relatively rigid and creasable material suitable for erection into a bottle carrier or carton for double rows of bottles and preferably is composed of cardboard or reinforced paper. This strip is provided at its middle portion and on its inner surface with parallel creases 2—2' adapted, when the material is bent at right angles along the same, to provide a bottom 3 for the carton, and in the embodiment shown, to provide the required flexibility to enable a relative sliding movement of the flaps and fastening means at the opposite ends of the strip. Said strip 1 is provided with side-wall sections 5—5' having hinge or foldable connections with said bottom and bendable at right angles to the bottom section. Said strip having a bottom and

side walls thus forms, what I shall term, the body of the carton.

The said strip 1 is, in the form illustrated, provided at opposite sides of the bottom creases 5 2-2' and also on the inner surface, with parallel creases 4-4'. These creases are positioned to limit the length of the wall sections 5-5' to a height less than the length of the bottle to be carried and preferably to a height extending to 10 a point below the neck of the bottle, and also to provide a hinged or foldable connection between the walls or body of the carton and neck-engaging members or sections 7-7', bendable again in the same direction and in the form illustrated being bent in an inclined plane relatively to the wall sections. The widths of the members or sections 7-7' will be determined by parallel creases 6-6' depressed in the opposite or external surface. The neck-engaging members 7-7' 15 each have elliptical longitudinal-extending bottle-insertion apertures 8 through which the top of the bottle is adapted to be projected and the upper and lower edges 8'-8" of which are adapted to abut against opposite sides of the bottle. 20 25 Connected or applied to the top of each of the neck-engaging sections 7-7' are handle sections or flaps 9-9' which are adapted to extend vertically and to abut against each other between the two rows of bottles and in accordance with my invention, these abutting flaps or handle sections are provided with hand holes registering with 30 each other to permit ready gripping and carrying of the carrier, and the flaps are securely fastened together and are preferably movable in opposite directions about the parallel creases 6, 6' 35 for the purpose hereinafter specified.

As illustrated, instead of cutting away the flexible material of the carrier to form hand holes or apertures 9a, 9b, which as illustrated are elliptical in conformation, I sever the material of the flaps or handle sections to provide a pair of complementary fastening tongues 10-11 preferably of identical configuration, though in reversed relationship to each other. Said tongues have base 40 portions 10'-11' connected by bendable or creased connecting portions 10b, 11b with their respective flaps 9, 9' and offset laterally with respect to each other, and also have rigid, non-foldable side-extension portions 10a-11a separated by kerfs 10c, 11c, extending between said flaps 9, 9' and tongues 10-11 and in alignment with said base connecting portions, said side extension portions and kerfs being also offset laterally with respect to each other. The tongues 45 50 55 10 and 11 are spaced as at 9c, 9d, 9e, and 9f from the adjacent edges of the holes 9a, 9b.

In manipulating the fastening elements, said tongues are initially bent about said base connecting portions to cause projection thereof toward each other. This may be accomplished by bending the flaps 9, 9' outwardly and simultaneously bending the tongues 10-11 inwardly toward each other. Said tongues may then be slid into engagement and be caused to project through opposite openings or hand holes by a relative sliding movement of the flaps. After such projection and interengagement, the tongues will abut at their outer edges against the bottles or goods carried by the carrier or carton. To release the tongues from engagement, the flaps may be bent outwardly from their abutting relationship like opening a book and thereupon, upon a sliding movement in the opposite direction, the 60 65 70 75 tongues may be disengaged.

In Fig. 8 I have shown a modified form of tongues in which the ends are similarly tapered as at 14, 14' and 15, 15' these tapered ends being formed with straight lines instead of curves as illustrated in Figs. 1, 6, and 7. In other respects 5 the device shown in Fig. 8 is similar to that shown in Figs. 1 to 7.

Having described my invention, I claim:—

1. A flexible carrier or carton embodying, in combination a flexible body having a pair of abutting flaps provided with a handle opening and a pair of opposing tongues formed unitarily with the flaps, mounted in said openings and mutually slidable laterally into engagement one behind the other, each comprising a tongue member having 10 a base portion connected to the flap and being offset laterally from the base portion of the opposing tongue and provided with a rigid side-extension portion extending laterally from said base portion and separated by a kerf extending 15 between said extension portion and the flap, said tongue members being foldable about an axis extending along said base portion to pass through the opening in the opposite flap and to extend at right angles thereto, said tongues also having 20 leading ends, each provided with a tapered tip above the longitudinal center line of the tongue, and following ends each having a tapered tip below said longitudinal center line of the tongue.

2. A flexible carrier or carton embodying, in 30 combination a flexible body having a pair of abutting flaps provided with a handle opening and a pair of opposing tongues formed unitarily with the flaps, mounted in said openings and mutually slidable laterally into engagement one 35 behind the other, each comprising a tongue member having a base portion connected to the flap and being offset laterally from the base portion of the opposing tongue and provided with a rigid side-extension portion extending laterally from 40 said base portion and separated by a kerf extending between said extension portion and the flap, said tongue members being foldable about an axis extending along said base portion to pass through the opening in the opposite flap and to extend 45 at right angles thereto, said tongues also having leading ends, each provided with a tapered tip above the longitudinal center line of the tongue, and following ends each having a tapered tip below said longitudinal center line of the 50 tongue and said tapered tips being formed by curved edges.

3. A flexible bottle carrier or carton comprising, in combination, a strip of flexible material having parallel creases at its middle part to provide between such creases a carton bottom and body parts at opposite sides of said creases, said body parts having additional parallel creases to provide side-wall portions, a pair of inclined members extending toward each other and abutting each other at their top edges and a pair of abutting flaps connected to said inclined members and bendable outwardly at their bases, said flaps being provided with corresponding openings, a pair of opposing tongue members formed unitarily with said body parts and extending into said flap openings, each tongue member comprising a connecting portion connected to a body part and being offset laterally from the connecting portion of the opposing tongue member and a rigid side-extension portion separated by a kerf extending between said side-extension portion and body part and disposed laterally from said connecting portion, said tongue members being 55 60 65 70 75 80 85 90 95 98

bendable only about an axis extending parallel with said kerf to project at substantially right angles to the flap, said carton bottom part being distortable to permit the opposite side-wall and flap parts to be swung out of and into alignment and to provide a lateral movement therebetween, and said rigid side-extension portions of

the tongue members being slidable laterally into interengagement behind each other during said lateral movement and said tongue members extending through the corresponding openings in opposite flaps.

CLAUDE D. KEITH.
